(57) CLAIM

The ornamental design for a garment with combination hat and hood, as shown and described.

DESCRIPTION

FIG. 1 is a perspective view of a garment with combination hat and hood showing my new design;

FIG. 2 is a perspective view thereof showing the garment;

FIG. 3 is a front view thereof;

FIG. 4 is a rear view thereof;

FIG. 5 is a side view thereof;

FIG. 6 is a side view thereof;

FIG. 7 is a top view thereof; and,

FIG. 8 is a bottom view thereof.

The broken line showing of the garment and wearer is included for the purpose of illustrating environment and forms no part of the claimed design.
